US00D611663S

(12) **United States Design Patent**
Bergschneider et al.

(10) **Patent No.:** **US D611,663 S**
(45) **Date of Patent:** **** Mar. 9, 2010**

(54) **TOOL CARRYING HARNESS WORN BY PETS**

(76) Inventors: **Perry Bergschneider**, 15431 Haney Rd., South Holland, IL (US) 60473; **Richard Bergschneider**, 15431 Haney Rd., South Holland, IL (US) 60473

(**) Term: **14 Years**

(21) Appl. No.: **29/325,188**

(22) Filed: **Sep. 26, 2008**

(51) **LOC (9) Cl.** **30-04**

(52) **U.S. Cl.** **D30/152**

(58) **Field of Classification Search** **D30/144, D30/145, 161, 169, 199; 199/850, 863, 856-858, 199/174, 792, 907; 224/42.11, 241, 582, 224/505; 54/44.1; D3/231; 441/127, 115, 441/55, 80, 136, 88, 106, 108**
